UNITED STATES PATENT OFFICE.

ARTHUR J. LAWSON, OF CHICAGO, ILLINOIS.

BORDER-LIGHT.

1,284,912.

Specification of Letters Patent. Patented Nov. 12, 1916.

Application filed August 31, 1916. Serial No. 117,928.

To all whom it may concern:

Be it known that I, ARTHUR J. LAWSON, a citizen of the United States, and a resident of the city of Chicago, county of Cook, and State of Illinois, have invented certain new and useful Improvements in Border-Lights, of which the following is a specification.

My invention relates to improvements in border lights especially adapted for use along the border of a stage in a theater or as foot lights therefor, the object of the invention being to provide a simple and efficient construction of this character adapted to readily supply different colored lights for the stage. Other objects will appear hereinafter.

The invention consists in the combinations and arrangements of parts hereinafter described and claimed.

The invention will be best understood by reference to the accompanying drawings forming a part of this specification, and in which;

Fig. 1 is a face view of a border light embodying my invention, shown with one of the transparencies employed therein partially raised to give a view of the interior,

Fig. 2, an enlarged section taken on line 2—2 of Fig. 1,

Fig. 3, an enlarged section taken on line 3—3 of Fig. 1,

Fig. 4, an enlarged face view of one corner of the transparency employed in the construction, and

Fig. 5, a section taken on line 5—5 of Fig. 2.

The preferred form of construction as illustrated in the drawings comprises a suitable housing made of sheet metal, said housing consisting of a top portion 6, sloping side portions 7 and 8 and a lower extension 9 arranged as indicated to form a housing having an upwardly sloping open side 10 as indicated. The housing is divided by a plurality of partitions 11 into a plurality of lighting compartments and channel members 12 are secured along the open edges of said compartments in position to receive transparency frames 13. The frames 13 are formed of two separable rectangular frames secured together by means of cotter pins 13' arranged at intervals and a colored transparency 14 of gelatin or similar other suitable material is secured between said separable frames. Wires 15 are arranged in

each of the frames 13 to reinforce the transparency 14 as indicated. By this arrangement it will be observed that different colored transparencies may be readily inserted or removed so as to provide for different colored lights for a stage or the like.

A wiring compartment or housing 16 is secured along the top of the light housing and is itself provided with a removable cover 17 in the form of a channel as shown. The cover 17 carries a plurality of electric light sockets 18 suitably connected in circuits by means of suitable wires arranged in the housing 16 and adapted to receive the corresponding connections 19 of corresponding electric light bulbs 20, as indicated, the top 6 of the housing 11 being provided with suitable openings 21 adapted to permit the passage of said connections as indicated. Ventilating openings 22, 23 and 24 are provided as indicated to permit of the escape of heated air and suspension chains 25 are also provided for suspending the light when desired.

The construction set forth constitutes a simple and efficient one for the purpose which may be readily mounted in operative position and which may be readily changed to give different light effects. The arrangement is also such that overheating of the housing and the surrounding parts is prevented.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A border light comprising a housing; partitions dividing said housing into compartments, there being openings through the top of each of said compartments; a wiring compartment arranged in said housing above the openings in the tops thereof; electric light sockets in said wiring compartments registering with the openings in the top of said housing; and electric light bulbs in the different compartments in said housing and having connections extending

through said openings and engaging said sockets, substantially as described.

2. A border light comprising a housing having a sloping open side; partitions dividing said housing into compartments, there being openings through the top of each of said compartments; guides along the edges of the open sides of said compartments; removable frames slidable in 5 said guides; colored transparencies in said frames; a wiring compartment arranged in said housing above the openings in the tops thereof; electric light sockets in said wiring

compartments registering with the openings in the top of said housing; and electric light bulbs in the different compartments in said housing and having connections extending through the side openings and engaging with said sockets, substantially as described.

In testimony whereof I have signed my name to this specification in the presence of two subscribing witnesses.

ARTHUR J. LAWSON.
